(57) CLAIM

The ornamental design for a ring pet treat, as shown and described.

DESCRIPTION

FIG. 1 is front, top and left side perspective view of a first embodiment of a ring pet treat according to the new design;

FIG. 2 is a back, bottom and right side perspective view of the embodiment of FIG. 1;
FIG. 3 is a front view of the embodiment of FIG. 1;
FIG. 4 is a back view of the embodiment of FIG. 1;
FIG. 5 is a left side elevation view of the embodiment of FIG. 1;
FIG. 6 is a right side elevation view of the embodiment of FIG. 1;
FIG. 7 is a top plan view of the embodiment of FIG. 1;
FIG. 8 is a bottom plan view of the embodiment of FIG. 1;
FIG. 9 is front, top and left side perspective view of a second embodiment of a ring pet treat according to the new design;
FIG. 10 is a back, bottom and right side perspective view of the embodiment of FIG. 9;
FIG. 11 is a front view of the embodiment of FIG. 9;
FIG. 12 is a back view of the embodiment of FIG. 9;
FIG. 13 is a left side elevation view of the embodiment of FIG. 9;
FIG. 14 is a right side elevation view of the embodiment of FIG. 9;

FIG. 15 is a top plan view of the embodiment of FIG. 9;
FIG. 16 is a bottom plan view of the embodiment of FIG. 9;
FIG. 17 is front, top and left side perspective view of a third embodiment of a ring pet treat according to the new design;
FIG. 18 is a back, bottom and right side perspective view of the embodiment of FIG. 17;
FIG. 19 is a front view of the embodiment of FIG. 17;
FIG. 20 is a back view of the embodiment of FIG. 17;
FIG. 21 is a left side elevation view of the embodiment of FIG. 17;
FIG. 22 is a right side elevation view of the embodiment of FIG. 17;
FIG. 23 is a top plan view of the embodiment of FIG. 17;
and,
FIG. 24 is a bottom plan view of the embodiment of FIG. 17.
The broken lines shown in FIGS. 1-14 illustrate portions of the ring pet treat that form no part of the claimed design.
